UNITED STATES PATENT OFFICE.

JOHN M. LEWIS, OF NEWPORT, AND NORMAN R. BRICE, OF COVINGTON, KY.

DESIGN FOR MEDAL BATTERIES.

SPECIFICATION forming part of Design No. 11,796, dated June 1, 1880.

Application filed May 3, 1880. Term of patent 3 $\frac{1}{2}$ years.

To all whom it may concern:

Be it known that we, JOHN M. LEWIS, of Newport, in the county of Campbell, State of Kentucky, and NORMAN R. BRICE, of Covington, in the county of Kenton and State of Kentucky, have invented and produced a new and original Design in Miniature Galvanic Batteries, which design is fully set forth in the following specification and accompanying drawing, in which the engraving represents a face view of the design.

It is formed of an outside circle of metal, A, the inner edge of which is formed in a wave-line having six points or enlarged parts, in each of which we cut out a portion, A', semi-circular in form.

The inner part of the design is composed of six pairs of heart-shaped pieces, C, with their apex pointing to the center, and ranged at even distances apart around the inner surface of the outer circle, A. Each of these heart-shaped pieces C is composed of two different pieces of metal. The two combined thus form the heart-shaped part, and both are provided with stems, which engage in the semicircular opening A' in the outer circle, A.

Centrally is a six-pointed star, B, having a perforation in the middle.

Having described our invention, what we claim as new, and desire to secure by Letters Patent, is—

The design for miniature galvanic batteries, composed of an outer circle, A, having on its inner edge a wave-line and six semicircular detents, A', which secure the stems of six heart-shaped bimetallic plates, C, ranged about the interior of the circle A, and having centrally the six-pointed star B, as herein set forth.

In testimony that we claim the foregoing we have hereunto, this 30th day of April, A. D. 1880, subscribed our names in presence of witnesses.

JOHN M. LEWIS.
NORMAN R. BRICE.
